FIG. 1

FIG. 1 is a front view of a building, showing my new design.

FIG. 2 is a side elevational view thereof as viewed from one side.

FIG. 3 is a side elevational view thereof as viewed from the opposite side.

FIG. 4 is a top plan view thereof.

In the drawings, for simplicity's sake, the sloped portions of the roof have been shown as being partially covered by shingles, but it is to be understood that the entire sloped portion of the roof is covered by the shingles.

I claim:

The ornamental design for a building, as shown and described.
